UNITED STATES PATENT OFFICE

CARL MATTSON, OF NEW YORK, N. Y.

COLLAPSIBLE WINDOW FRAME

Application filed November 20, 1929. Serial No. 408,512.

This invention relates to a collapsible window frame, the object being to provide an improved construction wherein a window frame is presented having the usual appearance but with the parts so constructed that the parting strips may be easily moved to one side, so that the window sashes may be swung inwardly or outwardly, as desired, for cleaning the window pane or for other purposes.

Another object of the invention is to provide a collapsible window frame wherein the parting strips are hingedly mounted at the top and associated with means at the bottom for swinging them in and out, so that they may be moved to a functioning or non-functioning position.

An additional object is to provide in a window frame means for guiding a weight used in connection with the sashes, the same being associated with a closure and lock therefor, whereby access may be had to the weight at any time.

In the accompanying drawing,

Figure 1 is a fragmentary elevation showing part of a window with certain parts broken away illustrating an embodiment of the invention;

Figure 2 is a sectional view through Figure 1 approximately on the line 2-2;

Figure 3 is a perspective view of the parting strips shown in Figure 1;

Figure 4 is a sectional view through Figure 2 on the line 4-4;

Figure 5 is a sectional view through Figure 4 on the line 5-5;

Figure 6 is a sectional view through Figure 4 on the line 6-6;

Figure 7 is a fragmentary plan view showing the lock embodying certain features of the invention;

Figure 8 is a sectional view through Figure 7 on the line 8-8;

Figure 9 is a detail perspective view of the locking bolt shown in Figure 7.

Referring to the accompanying drawings by numerals, 1 indicates the frame as a whole, 2 and 3 the upper and lower sashes, and 4 and 5 the panes of glass carried by these sashes. The frame 1 on each side is pro-

vided with inner and outer members 6 and 7, as shown in Figure 5, and a side member 8, whereby a chamber 9 is produced. In this chamber the respective weights move. Opposite the member 8 are arranged inner side members 10 and 11 separated by the respective parting strips 12, 13 and 14. Only one side of the window frame and associated parts have been shown, but it is to be understood that the same structure is provided on the opposite side. The side member 11 is provided with a pulley wheel 15 of a construction that is in common use today. The side member 10 is likewise provided with a similar structure and the respective pulleys are supplied with cords 16 of any desired kind, said cords extending downwardly so that the cord associated with member 10 is connected with sash 2, while the cord 16 associated with member 11 is connected to sash 3, as shown in Figure 4. This cord is also connected to a weight 17 in any suitable manner. Sash 3 is provided with a resilient strip 18 secured by the screw or other means to the sash 3 at 19 and positioned to flex in the cut-away portion 20. This strip is provided with a turned-over bifurcated end 21 which accommodates the end of the cord 16, so that the knot 22 will engage the bifurcated end 21 and thereby connect the cord and weight with the sash to counterbalance the weight of the sash. This construction is substantially the usual construction now on the market, except for the particular construction of the strip 18 with its bifurcated end 21. The knot 22 when in operative position is arranged as shown in Figure 4, but when the sash 3 is to be removed the knot is swung outwardly and away from end 21 and then moved to engage the bifurcated end 23 of a locking bolt 24 shown particularly in Figures 7 to 9. The bolt 24 is slidable and rockable in the cut-away portion 25, which cut-away portion has an offset 26 for accommodating the end 23 when the bolt is to be held in an unlocked position and with an extension 27 when the bolt is to be held in a locked position. Bolt 24 is carried by a fitting 28 and is adapted to move upwardly and downwardly. When moving down-

wardly as shown in Figure 7, the bolt is forced through an apertured fitting 29 and then rotated until the bifurcated end 23 is in extension or notch 27. Bolt 24 is provided with a lug 30 which slides through a suitable groove 31 in fitting 29 as the bolt moves downwardly, and when the bolt is turned for end 23 to fit into notch 27 extension 30 will move to a point beneath the fitting 29 but out of alignment with the groove 31. This will lock the bolt against accidental movement. The fitting 29 is carried by the cover plate or door 32 which is swingably supported by the hinge 33. A similar structure is provided for the member 10, as shown in Figure 2. Whenever it should be desired to remove the weight 17 door 32 is opened and the weight removed, and after the same has been replaced the door may be closed and locked by bolt 24. It will, therefore, be noted that the bolt 24 acts in the double capacity of a bolt or lock for holding door 32 closed and as an anchor for receiving knot 22 in the cord 16 for holding the cord and weight in a desired position while the sash is removed. If this arrangement were not provided or some similar arrangement, it would be necessary to tie an article to the end of cords 16 or to form the same into a big knot so that the end would not pass the pulley 15.

The weight 17, as shown in Figure 4, is guided by a square tube 34 and by a substantially U-shaped guide 35. A similar structure is provided for member 10, whereby the respective weights will be properly guided and will have a portion thereof always within one of the guides. A bracket or other suitable support 36 is provided near the bottom of guide 35 so as to prevent the weight from dropping downwardly beyond a certain point, in case the cord 16 should break. This will protect the bar 37 and tube 37' (Figure 6) and associated parts against being injured. As shown particularly in Figure 6, bar or rod 36 is connected with links 38 and 39. Link 38 carries a shaft 40 rotatably mounted at one end in a bearing bushing 41. Link 39 is rigidly secured to a socket member 42 which is rotatably mounted in bushing 43. Socket 42 is preferably square or some other irregular shape so as to receive a key 44, whereby link 39 may be moved and power transmitted to shaft or bar 37 and associated parts for swinging the same as indicated in dotted lines in Figure 4. The rod or bar 37 extends through slots 45 and 46 formed in the end sections 47 and 48 of the parting strips 12 and 13. Sections 47 and 48 are connected by a rear section 49, as shown in Figure 3, so that the two parting strips are rigidly connected together and swing back and forth as a unit. The upper end of each of these strips is provided with a reinforcement 50, and through this reinforcement and

the strips are formed apertures 51 adapted to receive the pivotal pin 52, whereby the parting strips may be swung back and forth. Ordinarily, the parting strips are arranged as shown in Figures 4 and 5, but when the key 44 is used and these strips are swung inwardly members 12 and 13 will move back until their outer edges will be substantially flush with members 10 and 11. This will free the window sashes so that they may be removed or swung out of the way, as preferred. In this way the parting strips may be easily moved out of the way to free the window sashes and likewise they may be quickly and easily swung back into operative position so as to hold the sashes in their proper places. It will be noted that the parting strips, or at least, the two inner parting strips are easily moved into operative position and easily moved to an inoperative position. It will also be noted that the cords 16 are removably connected with the sashes and are so formed as to readily interlock with the bifurcated end 23 of lock 24. These different structures are associated together so that the window frame sash and associated parts will have substantially the usual appearance of a device of this kind, but presenting these special features in such a manner that the sashes may be quickly removed while holding the cords and other parts in place.

What I claim is:—

1. A window of the character described, including a pair of swinging parting strips, a sash cord and weight, means for removably connecting said cord with a sash, a hingedly mounted door forming part of said frame, and a lock mechanism for locking said door normally closed, said lock mechanism including a swinging and sliding bolt, said bolt having a portion acting as a lock and a portion acting as a handle, said handle being bifurcated and positioned to receive the end of said sash cord when the same has been removed from said sash, whereby the cord will not accidentally move to a position within the frame.

2. A window frame of the character described, including means forming a weight passageway, said means including a door arranged at the bottom of the frame, whereby access may be had to said passageway at the lower end, and a reciprocating and rotatable bolt acting when in one position to lock said door closed and when in a second position as anchoring means for a sash cord.

CARL MATTSON.
